HIGH FREQUENCY SIGNALING SYSTEM

Filed April 18, 1922

Inventor:
Edward Austin,
by *Albert S. Davis*
His Attorney.

UNITED STATES PATENT OFFICE

EDWARD AUSTIN, OF SCHENECTADY, NEW YORK, ASSIGNOR TO GENERAL ELECTRIC COMPANY, A CORPORATION OF NEW YORK

HIGH-FREQUENCY SIGNALING SYSTEM

Application filed April 18, 1922. Serial No. 555,376.

My present invention relates to signaling systems and more particularly to signaling systems of the so-called carrier current type in which high frequency signaling currents are conducted over wires.

The object of my invention is to provide a signaling system in which connections employed for distributing power may also be employed for signaling by means of carrier currents and receiving devices for the signaling currents may be connected to the distribution system in the same way that any current consuming device such as an incandescent lamp is connected thereto.

One typical case in which my invention may be employed to advantage is that of a secondary distribution system for supplying electric current for lighting or power purposes to individual consumers. Such a system usually comprises a central station from which current is distributed through a plurality of feeder circuits to an entire community. In such a case I may impress the high frequency signaling currents upon the bus bars of the central station and they will be distributed throughout the entire distribution system. Any consumer of current for lighting or power purposes who is provided with a suitable receiving apparatus may then connect his receiving apparatus to a lamp socket or other outlet in the house wiring system and receive the signals sent out over the system. The system is particularly adapted for the broadcasting of news or music, etc., as any number of customers of the power system may simultaneously receive the signals transmitted. It is not however limited in its usefulness to this particular application as by suitable modification in the receiving apparatus and by the provision of suitable calling apparatus any individual consumer may be called as in an ordinary telephone system and communication may be had between any two customers of the power system without

interfering with the use of the system by other individuals at the same time.

The novel features which I believe to be characteristic of my invention are set forth with particularity in the appended claims. My invention itself, however, both as to its organization and method of operation will best be understood by reference to the following description taken in connection with the accompanying drawing in which I have shown diagrammatically one way whereby my invention may be carried into effect.

I have indicated in the drawing a central power station 1 in which a source of current 2 supplies current to the bus bars 3, 4. From these bus bars current is supplied to the feeder circuits 5, 6 and 7. The potential of these feeder circuits will ordinarily be fairly high and current will be supplied to wiring systems in buildings through stepdown transformers 8, 9 and 10. Current from the secondaries of these transformers will be supplied to a plurality of current consumption devices 11, such as incandescent lamps, motors, heating devices, etc.

In the present case I have indicated a signal transmitter 12 connected to the bus bars 3 and 4 through condensers 13, of comparatively low capacity which prevent the flow of current from the power distribution system in the signal transmitting apparatus. The transmitter 12 may be of any form suitable for producing high frequency currents and modulating them. A receiving apparatus for receiving the signal transmitted may be connected by means of a plug 14 to any socket 15 in place of a lamp or other current consuming device. The receiving circuit connected to the plug 14 may include a filter circuit made up of condensers 16 and inductances 17 for preventing the normal current in the distribution system from affecting the receiving apparatus which I have illustrated as being of the usual vacuum tube type with an indicating device 18, which may be a loud speak-

ing telephone, in the plate circuit. It will of course be understood that any form of detecting and amplifying apparatus which is employed with high frequency signaling currents transmitted over grounded circuits or through the ether, may be employed in producing an indication of currents transmitted in the manner which I have described. It may be desirable in some cases to prevent the signaling current from being distributed over the entire distribution system. Feeder 6, for example, may supply current for street lighting purposes only and any signaling current sent over this feeder would be entirely lost. In such a case choke coils 19 may be inserted in the feeder to prevent the high frequency current from flowing in that portion of the distribution system.

What I claim as new and desire to secure by Letters Patent of the United States, is:—

1. A combined power and broadcasting system comprising in combination a source of alternating power current having a low frequency, a power transformer having one winding connected across said source of alternating current power, a power consumption circuit connected across a second winding of said transformer, means for supplying a high frequency carrier electromotive force to the first winding in parallel with the electromotive force of said source of alternating current power, said carrier electromotive force having a frequency materially higher than the usual voice frequencies, means for modulating said carrier electromotive force with currents of voice frequency, and a carrier current receiver connected across the second of said transformer windings through a coupling means which is effective for transmitting currents of said carrier frequency but substantially ineffective in transmitting currents of the power frequency, said receiver being adapted to detect and reproduce said voice frequency.

2. A combined power and broadcasting system comprising in combination a source of alternating power current having a low frequency, a power transformer having one winding connected across said source of alternating power current, a power consumption circuit connected across a second winding of said transformer, means for supplying a broadcasting carrier wave frequency electromotive force in parallel with the electromotive force of said source of alternating current power, means for modulating said broadcasting carrier wave frequency electromotive force with currents of voice frequency, and a broadcast receiver coupled across said second winding of said transformer through a coupling means which is effective for transmitting currents of said carrier frequency but substantially ineffective in transmitting currents of the power frequency, said re-

ceiver being adapted to detect and reproduce said voice frequencies.

3. A system of distribution comprising a relatively high voltage low frequency power feed circuit and a lower potential power consumption circuit, a power transformer, said transformer having one winding connected across two conductors of said feed circuit and a second winding connected to said lower potential circuit, means for impressing modulated high frequency signaling electromotive forces across said two conductors of said feed circuit, said means comprising coupling means for said high frequency signaling electromotive forces offering extremely high impedance for currents of the power frequency, a plurality of current consumption devices operable at said low frequency and connected to said lower potential circuit, and a receiver adapted to detect and reproduce said modulations, said receiver being connected to said lower potential circuit in place of one of said current consumption devices and in parallel with other current consumption devices through coupling means which is effective for the signaling frequency but which offers an extremely high impedance to currents of the power frequency.

4. A system of distribution comprising a relatively high voltage low frequency power feed circuit and a lower potential power consumption circuit connected to said feed circuit through a distribution transformer, means for impressing modulated high frequency signaling electromotive forces across two conductors of said feed circuit, said electromotive forces being impressed in parallel with the relatively high voltage applied to said feed circuit a plurality of current consumption devices operable at said low frequency and connected to said lower potential circuit, a receiver adapted to be connected to said lower potential circuit in place of one of said current consumption devices and in parallel with other current consumption devices for receiving said modulated high frequency currents and producing an audible indication, and means for excluding power currents from said receiver.

5. The combination in a signaling system of an alternating current power distribution system for distributing energy to electric lamps or other current consuming devices comprising a central power station, a plurality of feeder circuits of comparatively high voltage connected to bus bars in said power distribution system, a plurality of lower potential circuits connected to said feeder circuits through transformers and having current consumption devices connected thereto, said transformers each comprising two inductively related windings, one of said windings comprising a portion of one of said lower potential circuits, the other of said windings being connected across one of said feeder cir-

cuits, means for impressing broadcast frequency signaling electromotive forces upon said bus bars in parallel with the power electromotive force supplied to said bus bars,
5 means comprising a receiver adapted to be connected across any one of said low potential circuits in place of a consumption device for receiving said broadcast signals and producing an audible indication therefrom, and
10 means for excluding power currents from said receiver.

In witness whereof, I have hereunto set my hand this 17th day of April, 1922.

EDWARD AUSTIN.
